UNITED STATES PATENT OFFICE

RUSSELL T. SMITH, OF CINCINNATI, OHIO, ASSIGNOR TO THE CROSLEY RADIO CORPORATION, OF CINCINNATI, OHIO, A CORPORATION OF OHIO

WATER COOLER

Application filed May 31, 1929. Serial No. 367,320.

My invention relates to water coolers, adapted to employ for the purpose of cooling the water, a portable refrigeration unit.

It is my object to provide a simple construction, in which an elevated vessel of water may be cooled and used, and the water cooled by passing through a chamber into which is inserted a refrigerating device. The refrigerating device is of the type shown 10 and described in application for patent Serial No. 201,904, filed June 27, 1927, by D. F. Keith. The design of the cabinet is such as to permit ready insertion and removal of the refrigerating unit, and to deliver the 15 cooled water at a convenient point for use.

I accomplish my objects by that certain construction and arrangement of parts to be hereinafter more specifically pointed out and claimed, and the novelty in the illustrated 20 example duly claimed.

In the drawings:

Figure 1 is a side elevation of the cabinet. Figure 2 is a rear elevation thereof.

The cabinet is formed of a suitable metal 25 frame on which a top plate 1, and side plates 2 are secured. The top of the cabinet when used with a bottle of water, is equipped with a well 3, with an external support 4 for holding a bottle 5 so that its neck extends into the 30 well.

Extending from the well is a tube 6 which passes down into the lower half of the cabinet, said lower half being equipped with insulated walls 7. The pipe may be coiled in 35 the bottom of this compartment and it then passes upwardly again, and terminates in a water tap 8 which extends to the outside of the cabinet.

The top half of the cabinet is equipped with 40 a hinged plate 9 at one side, which plate is hinged at 10 near the top of the insulated compartment. This door has holes in it for dowels 11^a on a plate 11 which closes the side of the cabinet above the hinged plate. This 45 plate 11 has a clearance slot 11^b for the connecting tube and handle of the refrigerating unit. The top of the insulated compartment is formed of an insulated lid or cover 12, which has clearance for the connecting tube 50 of the unit, as at 13.

The unit, as in all types of portable refrigeration devices is formed of a generator-absorber shell 14, a connecting element in this instance, a single tube 15 and a condenser evaporator 16. The connecting tube is fitted with a handle 17. The exterior of the cabinet may be fitted with a cross brace 18 against which the shell 14 lies when the device is in use.

In placing the unit into the cabinet the 55 plate 11 is lifted away by folding it down together with the hinged plate or flap and then removing it. The lid is then removed from the insulated compartment. The space above the compartment is sufficiently large 65 for the condenser-evaporator shell to be inserted and lowered into the cooling compartment.

The lid is then replaced on the compartment, the hinged flap folded up to support 70 the connecting tube of the unit, and the closing plate mounted by setting its dowels into the holes in the flap and pushing it into place.

The water bottle may then be set into place, 75 and the device is ready for use, since the condenser-evaporator becomes quite cold which cools the water as it passes through the pipe or tube 7.

The whole device is simple and strong. It 80 provides for the proper clearances for the refrigeration unit, so that it can be inserted and removed for generation of the liquid refrigerant in the evaporator, and provides water at a convenient point for the user.

Having thus described my invention, what 85 I claim as new and desire to secure by Letters Patent, is:—

1. In a device of the character described, a cabinet having in its lower portion a refrigerating compartment suitably insulated, with a movable cover, a movable closure for that portion of one of the sides of the cabinet above said compartment, said closure having clearance for the connecting element between the portions of a portable refrigerating unit, the evaporator of which is inserted into the cabinet, the space above the compartment as disclosed by said side closure being sufficient 90 to permit of insertion of said evaporator, and 95

- tubular connection from an elevated source of supply of water passing down through the compartment and thence upwardly to a convenient point for use, where it is coupled with a tap that extends from the cabinet.
- 5 2. In a device of the character described, a cabinet having in its lower portion a refrigerating compartment suitably insulated, with a movable cover, a movable closure for that portion of one of the sides of the cabinet above said compartment, said closure having clearance for the connecting element between the portions of a portable refrigerating unit, the evaporator of which is inserted into the cabinet, the space above the compartment as disclosed by said side closure being sufficient to permit of insertion of said evaporator, and tubular connection from an elevated source of supply of water passing down through the compartment and thence upwardly to a convenient point for use, where it is coupled with a tap that extends from the cabinet, said removable closure being formed of a lower hinged section, and a removable section engaged removably in the hinged section, and constituting the major portion of the closure.
- 10 3. In a device of the character described, a cabinet having in its lower portion a refrigerating compartment suitably insulated, with a movable cover, a movable closure for that portion of one of the sides of the cabinet above said compartment, said closure having clearance for the connecting element between the portions of a portable refrigerating unit, the evaporator of which is inserted into the cabinet, the space above the compartment as disclosed by said side closure being sufficient to permit of insertion of said evaporator, and tubular connection from an elevated source of supply of water passing down through the compartment and thence upwardly to a convenient point for use, where it is coupled with a tap that extends from the cabinet, said removable closure being formed of a lower hinged section, and a removable section engaged removably in the hinged section, and constituting the major portion of the closure.
- 15 4. In a device of the character described, a cabinet having in its lower portion a refrigerating compartment suitably insulated, with a movable cover, a movable closure for that portion of one of the sides of the cabinet above said compartment, said closure having clearance for the connecting element between the portions of a portable refrigerating unit, the evaporator of which is inserted into the cabinet, the space above the compartment as disclosed by said side closure being sufficient to permit of insertion of said evaporator, and tubular connection from an elevated source of supply of water passing down through the compartment and thence upwardly to a convenient point for use, where it is coupled with a tap that extends from the cabinet, said removable closure being formed of a lower hinged section, and a removable section engaged removably in the hinged section, and constituting the major portion of the closure, said compartment having an insulated lid which has clearance for
- 20 the connecting element of the refrigerating unit.
